Design No. 12,038, dated November 23, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,038, dated November 23, 1880.

Application filed July 31, 1880. Term of patent 3½ years.

To all whom it may concern:

Be it known that I, EDUARD LEISSNER, of the city of New York, in the county and State of New York, have invented a new and original Design for Wall-Paper, of which the following is a specification.

This invention relates to a new and original design for wall-paper and similar fabrics.

It consists in the new arrangement and grouping of figures hereinafter more fully described.

The accompanying photograph illustrates a face view of wall-paper having my new design.

15 The letter A represents the body of my newly-designed wall-paper. B is the border of the same. The body A is formed of two groups, C and D. Group C consists of the scroll *a a a*, curving spirally inward upon itself, ornamented with the leaf *b* and projection *c*, and terminating in the ball-shaped ornaments *d*. From a point on the interior curve of the spiral *a* appears to grow the conventional flower *e*, which fills nearly the whole interior of the curve formed by the stripe *a*.

20 The group D is formed as follows: From the outside of the curving stripe *a*, at a point near the stem of the flower *e*, runs a curving stripe, *f f f*, from which branches off on the outside the leaf-shaped ornament *g*, and from the interior of this stripe *f f f* runs the branch *h*, with its leaves and berries, and also the large conventional flower *j*, the branch *h* and flower *j* nearly filling the interior of the curve formed by the stripes *f f f*.

25 Two parallel stripes, E and E, inclose the groups C and D in the photograph. These stripes are composed of a series of parallel bands, *g g*, one of which is dotted or beaded 40 with dots or beads *r r r*, as shown.

The border B consists of a vine, *m m m*, running in S-shaped connected curves. Upon this vine *m m m* are leaf-like projections *p p p*, and from it branch off alternately a leaf, *n*, 45 and a conventional bud, *o*, the leaf and the bud being placed alternately in the openings formed by the curving vine. Two parallel

stripes, K K, serve as borders to this vine. The stripes K K are composed of three plain parallel adjoining bands, the one in the middle being the widest.

I claim—

1. The design for wall-paper consisting of the vine *m m m*, with its projections *p p p* and alternate leaf *n* and bud *o*, substantially as shown.

2. The design for wall-paper consisting of the bud-like figure *o*, substantially as shown.

3. The design for wall paper consisting of the vine *m m m* with bud-like figures *o* thereupon, substantially as shown.

4. The design for wall-paper consisting of the border B, composed of the vine *m m m*, with its ornamentation of buds *o*, and leaves *n*, in connection with the stripes *k k*, substantially as shown.

5. The design for wall-paper consisting of the stripes E E and groups C and D, substantially as shown.

6. The design for wall-paper consisting of the flower-like figure *e*, substantially as shown.

7. The design for wall-paper consisting of the spirally-curving band *a a a* and the ornaments *b c d e*, substantially as shown.

8. The design for wall-paper consisting of the curving band *a a a* and the flower-like figure *e*, substantially as shown.

9. The design for wall-paper consisting of the curving band *f f f*, with its ornaments *g*, *h*, and *j*, substantially as shown.

10. The design for wall-paper consisting of the group C, composed of the figures *a b c d e*, and of the group D, composed of the figures *f g h j*, substantially as shown.

11. The design for wall-paper consisting of the connected groups C and D and of the stripes E E, substantially as shown.

12. The design for wall-paper consisting of the body A, stripes E E, border B, and stripes *k k*, substantially as shown.

EDUARD LEISSNER.
